HENRY O. ENGSTROM, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

SWITCH HANDLE.

Application filed May 14, 1924. Serial No. 713,276.

To all whom it may concern:

Be it known that I, HENRY O. ENGSTROM, a subject of the King of Sweden, residing at Bridgeport, in the county of Fairfield and 5 State of Connecticut, have invented certain new and useful Improvements in Switch Handles, of which the following is a specification.

My invention relates to electric switches, 10 and particularly to rotary snap switches. The object of my invention is to provide a handle having improved means for attachment to and actuating engagement with the rotary switch spindle.

15 In the accompanying drawings—

Fig. 1 is a side elevation of a rotary snap switch showing in vertical section a handle construction in which my invention is embodied in one form;

20 Fig. 2 is a section on the line 2—2, Fig. 1; and

Fig. 3 is a perspective of a detail of the handle.

The rotary snap switch to which the present handle may be applied, may be of any suitable character. To illustrate the invention, however, I have shown a flush switch of standard type, having an insulating base 15 on which the switch mechanism is 25 mounted and encased by the cover 16. Projecting through a hole in the top of the latter is the threaded end of the rotary switch spindle 17, from which laterally projects a fin 18, by means of which actuating engagement 30 between the switch handle and the switch mechanism is established.

The handle comprises an insulating button 19, axially pierced at 20 to accommodate the projecting stem of the switch spindle. 40 Bays 21 open from the spindle-way 20 to receive and engage the fin 18. The hole 20 opens to a well 22 at the outer end of the button 19, and inasmuch as the well 22 is of greater diameter than the hole 20, an annular shoulder 23 is afforded at the bottom of the well against which abuts one end of a coil spring 24. A marginal flange 25 at the head of a ferrule 26 engages the opposite end of the spring 24 and thus confines the 45 latter within the well 22 between the flange

25 and the abutment 23. The ferrule 26 is internally threaded to engage the threaded end of the spindle 17, and the lower end of the ferrule passes through the bottom of the well into the hole 20, where it is offset at 55 opposite points into the bays 21. The offsets 27 engage the shoulders 28 afforded by the upper ends of the bays, and thus retain the ferrule against escape, as well as against rotation with respect to the button 19.

60 Resting against the face of the boss 29, adjacent the cover 16, is a bearing washer 30 centrally apertured at 31 to accommodate the spindle 17, and having notches 32 formed therein, which register with the bays 21 in 65 the button to permit the fin 18 of the spindle to pass through the washer into one or the other of said bays. Spring lugs 33 struck from the washer incidental to the formation of the notches 32, enter the bays 21 and engage the walls thereof to prevent accidental detachment of the washer.

70 The attachment of the handle is readily understood. The portion of the spindle 17 extending beyond the fin 18 is of sufficient 75 length to engage the thread at the inner end of the ferrule 26 when the offsets 27 bear against the shoulders 28. As the handle is turned down on the spindle the fin 18 tends to limit the extent of the 80 threaded engagement between the ferrule and spindle. In order to secure a proper engagement, it is necessary during rotation of the button to hold it away from the cover 16, and thus clear the fin 18. When a sufficient engagement has been attained, however, and the fin 18 is in register with one 85 of the bays 21, the button 19 is released, whereupon the spring 24 forces the button against the cover and at the same time establishes the engagement of the fin 18 in 90 one or the other of the bays 21. The cover is thus held seated against the base 15, while an operative engagement is established between the handle and the spindle.

95 To remove the handle from the spindle it is necessary to draw the button outward against the effort of the spring 24, until the inner end of the button clears the fin 18. The handle may then be rotated in a direc- 100

tion to unscrew the ferrule from the spindle. As above stated the ferrule 26 is held at all times against rotation with respect to the button 19, by the offsets 27, which enter the 5 bays 21.

The construction is exceedingly simple and economical. The molding of the handle is readily accomplished, while both the attachment of the handle to the spindle and the 10 engagement of the spindle with the handle for rotation, are secure and efficient. The particular method of preventing rotation of the ferrule with respect to the button may be modified, for example by making the well 15 22 and the head flange 25 of the ferrule of non-circular contour. A pin piercing the spindle may be substituted for the fin 18. Other variations in structure will readily occur to those dealing with the matter, 20 which do not depart from what I claim as my invention.

I claim—

1. A rotary snap switch handle comprising an insulating button pierced to afford 25 a way for the threaded end of the rotary switch spindle, a lateral bay opening to the spindle way, means associated with the spindle and entering said way to establish drive connection between the handle and 30 spindle, and at the outer end of the button a well of greater diameter than the spindle way and to the bottom of which the latter opens, a spindle-engaging screw ferrule secured against rotation in said well but dis- 35 placeable toward the spindle, and a spring interposed between said ferrule and the bottom of the well and opposing the rectilinear displacement of the ferrule with respect to the button.
- 40 2. A rotary snap switch handle comprising an insulating button pierced to afford a way for the threaded end of the rotary switch spindle, a lateral bay opening to the spindle way, means associated with the spindle and entering said way to establish drive connection between the handle and spindle, and at the outer end of the button a well of greater diameter than the spindle way and to the bottom of which the latter opens, 45 a spindle-engaging screw ferrule arranged in said well and having at its outer end a laterally projecting flange, and at its inner end an offset below the bottom of the well to retain the ferrule against escape, and a spring interposed between the bottom of the well and the flange at the outer end of the ferrule and opposing the rectilinear displacement of the ferrule with respect to the button.
- 50 3. A rotary snap switch handle comprising an insulating button pierced to afford a way for the threaded end of the rotary switch spindle, a lateral bay opening to the spindle way, means associated with the spindle and entering said way to establish drive

connection between the handle and spindle, and at the outer end of the button a well of greater diameter than the spindle way and to the bottom of which the latter opens, a spindle-engaging screw ferrule arranged 70 in said well and having at its outer end a laterally projecting flange, and at its inner end an offset entering said lateral bay opening to the spindle way and serving to hold said ferrule against escape and also against 75 rotation with respect to the button, together with a spring interposed between the bottom of the well and the flange at the outer end of the ferrule and opposing the rectilinear displacement of the ferrule with respect to 80 the button.

4. In a rotary snap switch, a rotary spindle, a spindle driving element rigid therewith and extending laterally therefrom, in combination with a switch handle pierced 85 to afford a spindleway, a shoulder formed in said way, ferrule arranged in said way and engaging said handle against rotation with respect thereto, but free for longitudinal displacement, said ferrule and spindle 90 being adapted for screw connection, a spring interposed between the ferrule and shoulder to oppose longitudinal displacement of the ferrule in the handle, said handle being recessed laterally of the spindleway to receive 95 the spindle driving element on longitudinal displacement of the handle with respect to the spindle after a screw connection between the spindle and ferrule has been established.

5. In a rotary snap switch, a rotary spindle, a spindle driving element rigid therewith and extending laterally therefrom, in combination with a switch handle pierced to afford a spindleway, a shoulder formed in said way, a ferrule arranged in said way and engaging said handle against rotation with respect thereto, but free for longitudinal displacement, said ferrule and spindle 100 being adapted for screw connection, a spring interposed between the ferrule and shoulder to oppose longitudinal displacement of the ferrule in the handle, said handle being recessed laterally of the spindleway to receive the spindle driving element on longitudinal displacement of the handle with respect to the spindle after a screw connection between the spindle and ferrule has been established, and a bearing washer at the mouth of the spindleway, said washer being pierced in 105 register with said way and the lateral recess in the handle to receive the spindle-driving element.

6. In a rotary snap switch, a switch base, a cover overlying the same, a switch spindle projecting from the base through the cover, in combination with a handle pierced to receive the spindle, a floating ferrule supported within the way in the handle and held against rotation with respect to the handle, a spring opposing displacement of 110 115 120 125 130

said floating ferrule toward the switch cover, a screw connection between said ferrule and spindle for securing the handle upon the spindle, together with an independent drive connection comprising means rigid with and laterally projecting from the spindle, and a recess in the handle

adapted to receive said driving member upon the longitudinal displacement of the handle after the screw connection between the spindle and ferrule has been established. 10

In testimony whereof I have signed my name to this specification.

HENRY O. ENGSTROM.
